US00D582119S

(12) **United States Design Patent**
Chafe et al.

(10) **Patent No.:** **US D582,119 S**
(45) **Date of Patent:** **** Dec. 2, 2008**

(54) **LID FOR A CONTAINER**

(75) Inventors: **Adam J. Chafe**, Hudson, OH (US); **Stuart F. Bedford**, Hudson, OH (US); **Kenneth W. Erdmann**, Chagrin Falls, OH (US); **James E. MacDonald**, Medina, OH (US); **Dilip R. Tamhane**, Avon Lake, OH (US); **Oliver J. Ramsey**, Brunswick, OH (US); **Ronald D. Hudas**, Massillon, OH (US); **Charlie Watling**, Raleigh, NC (US); **Forrest A. Burney**, Raleigh, NC (US); **Bob Bruno**, Avon, CT (US); **Scott Belliveau**, Plainfield, IL (US)

(73) Assignee: **The Sherwin-Williams Company**, Cleveland, OH (US)

(**) Term: **14 Years**

(21) Appl. No.: **29/220,705**

(22) Filed: **Jan. 5, 2005**

(51) **LOC (8) Cl.** **07-07**

(52) **U.S. Cl.** **D32/54**

(58) **Field of Classification Search** D32/53.1, D32/54; 222/570; 220/570, 757, 754, 697, 220/507, 695, 793, 571, 571.1; 15/257.05, 15/257.06; 206/216; D3/276, 304

(57) **CLAIM**

The ornamental design for a lid for a container, as shown and described.

DESCRIPTION

FIG. 1 is a bottom perspective view of a container on which the lid is used.

FIG. 2 is a perspective view of a container on which the lid is used.

FIG. 3 is a bottom plan view of a lid for a container.

FIG. 4 is a side elevation view of a lid for a container.

FIG. 5 is a front elevation view of a lid for a container; and,

FIG. 6 is a top perspective view of a lid for a container.

The broken line showing the container in FIG. 2 is included for the purpose of illustration only and forms no part of the claimed design.
